UNITED STATES PATENT OFFICE.

HORACE B. HEWITT, OF INDIANAPOLIS, INDIANA.

FASTENING MEANS FOR SNATHE-NIBS.

1,245,917.

Specification of Letters Patent.

Patented Nov. 6, 1917.

Application filed September 30, 1915. Serial No. 53,367.

To all whom it may concern:

Be it known that I, HORACE B. HEWITT, a citizen of the United States, residing at Indianapolis, Marion county, and State of Indiana, have invented and discovered certain new and useful Improvements in Fastening Means for Snafe-Nibs, of which the following is a specification.

My invention relates to fastening means for nibs for snathes and its object is to provide a construction in which several operations now required in the manufacture and assemblage of the nib and the nib iron are dispensed with, thereby reducing the cost, and in which the nib iron is capable of being conformed to the contour of the snafe when originally applied, or of being adjusted to a new location on the snafe, merely by manipulation of the nib and without the use of formers or other tools for such purposes.

With this end in view, my invention is embodied in preferable form in the construction and arrangement hereinafter described and illustrated in the accompanying drawings.

In these drawings, Figure 1 is a longitudinal section through a nib or handle showing one form of my invention applied thereto; Fig. 2, a cross section on line 2—2 of Fig. 1; Fig. 3, a detail plan, partly broken away, of the strip constituting the nib iron before it is bent into shape to receive the snafe; Fig. 4, a detail side view; Fig. 5, a view similar to Fig. 1 of a modified form of the construction; Fig. 6, a section of the line 6—6 of Fig. 5, and Fig. 7, a longitudinal section of another modified form of the construction.

Referring to the drawings, and first to the construction illustrated in Figs. 1—4 inclusive, 1 designates the snafe of a scythe or cradle, and 2 indicates one of the handles or "nibs", as such handles are usually called, and which are adapted to project angularly from the snafe and to be grasped by the hands of the user in the operation of the scythe. This nib is made of wood and is adapted to be clamped to the scythe snafe by what is known as a nib-iron.

According to the usual construction, this nib-iron consists of a piece of stiff metal having a loop portion which surrounds the snafe and is adapted to be bent closely against the surface of the same by means of

a press or former, and which also has a 55 stem or shank which is adapted to extend through the nib and to have its outer end threaded so as to receive a nut fixed in the nib. In this construction the loop and the stem are, of course, integral and it is necessary to make the former of comparatively heavy metal in order that when the portions of the iron which constitute the stem or shank are brought together the shank member may be of sufficient strength to support 60 the nib, and of sufficient thickness and rigidity to permit threads to be tapped therein to receive the locking nut. The thickness of metal thus required in the loop necessitates the employment of a special former or 70 presser, heretofore referred to, for the purpose of pressing the loop tightly down against the surface of the snafe so as to hold the nib rigidly in position. Also, if it should be desired by the user to move the 75 handle to another location on the snafe it is necessary for him to use a heavy hammer in loosening the nib iron and driving it along the snafe and re-bending it to fit the different contour thereof at the new location, which differences exist by reason of the tapered form of the snafe.

In such construction, also, it is necessary to cut off that end of the stem or shank of the nib iron which projects beyond the outer 85 surface of the nib, and then to grind down this end so that the same may be flush with the outer surface of the nib and may have a smooth finish. Such projection of the end is necessary in the usual construction to 90 provide sufficient length to allow for irregularities in the size and surface contour of different snathes. These various operations entail the most considerable part of the expense of manufacture, and also the nib iron described can not be adjusted by the user except at great inconvenience.

My invention overcomes these objections and difficulties.

The nib-iron of the invention consists of a single continuous integral strip of thin, pliable steel which is adapted to be bent around the snafe to form a clamping loop strap 3, the ends of said strip being bent into a substantially U-shape in cross section, and being adapted to be pressed together edge to edge so as to form a substantially cylindrical stem or shank 4, projecting at an angle

from the snathe. The opposing members forming this shank are adapted to be held in position by means of a ferrule 5, which is slipped over the shank. A second and larger ferrule 5' fits over the ferrule 5. This ferrule 5' is provided with a substantially circular central opening 6, and with angled slots 7, extending from said central opening and adapted to fit over the loop member of the nib-iron so that the ferrule at its end will embrace said loop and bear against the snathe surface. The ferrule 5' is countersunk in its upper end to receive the inner end of the wooden nib or handle 2.

15 The stem 4 extends into this nib only a short distance and is interiorly screw threaded to receive the inner threaded end of a bolt 8, which bolt is provided at its outer end with a head 9, adapted to close the aperture 20 through the nib, and is also provided adjacent said head with a squared or other polygonal portion 10, which is adapted to be driven into the wood of the handle so as to prevent the bolt from turning independently 25 but to enable the handle and bolt to be turned together.

In this construction since the long bolt constitutes the main bearing and connecting member between the nib and the nib-iron, 30 and since the ferrule serves to sufficiently stiffen the stem of the iron to enable the same to retain the bolt, it is rendered possible to employ a loop or strap member of pliable metal capable of being bent closely 35 against the surface of the snathe to conform it to the contour of the snathe, notwithstanding variations in size or shape of the latter, and to effect this conformation merely by the adjustment of the nib itself.

40 In assembling the parts, the strip constituting the body of the nib-iron is folded together circumferentially and the ferrule 5 applied thereto in order to hold the ends together and then the loop or strap is slid over 45 the snathe to its proper position thereon. The ferrule 5' is then slipped on and the nib, carrying embedded therein the longitudinally extending bolt, is applied to the nib-iron, the threads of the bolt engaging 50 the threads in the stem of the iron, and when the nib is turned by hand, or by a suitable machine, the loop strap will be clamped tightly around and against the snathe, the nib being carried down against the ferrule, 55.

In the use of the device, should it be desired by the user to move the nib along the snathe to a different position, it is merely necessary for him to loosen the loop by unscrewing the nib and to then move the nib iron along the snathe to the new location and re-clamp the same by again screwing up the nib.

60 In Figs. 5 and 6, a modified form of the construction is employed, in which the nib-

iron is formed from a single integral piece of metal, but in this case such piece consists of a flat strip or plate of sheet steel adapted to be pressed into form to provide a loop or strap member 11, and an elongated shank 70 12. Said shank 12, as a result of the first pressing operation, is U-shaped in cross section, but is adapted to be closed into circular form by another pressing operation. In this construction, also, the loop or strap 75 member is of pliable metal capable of being bent and conformed closely to the contour of the snathe merely by the pressure induced through the tightening of the nib or handle. In this construction the shank extends 80 through the nib for a greater distance than in the previously described form, but terminates short of the outer end of the nib, thus also obviating the necessity of cutting off and grinding the end thereof. 85

The shank is exteriorly threaded at 13 at its outer end to receive a nut 14, which is adapted to be driven into a countersunk recess 15, formed in the end of the nib, the nut being so driven into the wood of the nib as 90 to turn therewith. By means of this nut the nib is adapted to be secured to the shank and also the loop or strap may be tightened by screwing up the nib as described with reference to the construction of Fig. 1. In 95 order to provide a smooth finish for the outer end of the nib, the recess therein is preferably adapted to be filled by a wooden plug 16.

In Fig. 7, another modified form of the 100 construction, is shown in which the pliable metal loop member is formed of a piece of comparatively thin band steel such as 17, and this strip or band is adapted to be welded at its ends 17' to a solid bolt 18, constituting the shank of the nib-iron and extending into the nib. 105

As in the case of the device of Figs. 5 and 6, the outer end of this shank is exteriorly screw threaded to receive a nut 19, which 110 is driven into the wood of the nib 20, at the inner end of the countersunk recess 21, a plug 22, being used to fill such recess.

In all of these forms of construction it will be seen that the clamping loop member 115 of pliable metal, capable of being conformed to the contour of the snathe merely by the adjustment of the nib itself, is an essential and distinguishing feature. In all of these forms, also, the operations of pressing the 120 loop strap by machinery against the snathe and cutting and grinding the usual projecting end of the nib-iron shank are dispensed with. The construction of Figs. 1 to 4 inclusive, also possesses other distinctive advantages with respect to cheapness, and the 125 commercial availability of the two parts of the nib-iron there shown, which may be of standard stock. In the construction of Figs. 1 and 5, the operation of welding usually re- 130

quired is dispensed with, while in the arrangement of Fig. 7, the welding is reduced to a minimum.

Having thus described my invention, what I claim is,

1. In combination with a nib for snathes, a nib-iron having a snathe engaging loop of relatively thin pliable metal to enable it to be bent by hand pressure applied to the loop,
- 10 a threaded shank for said loop, means carried by the shank and non-rotatably engaging the nib whereby the shank is caused through its threaded part to move longitudinally to tighten the loop when the nib is turned, and a ferrule bearing against the loop and having a socket to receive the inner end of the nib.
- 15 2. In combination with a snathe nib, a snathe engaging loop member of sufficient pliability and thinness as to be capable of being bent into close contact with the surface of the snathe by hand pressure applied to the nib, a separate rigid shank member to the inner end of which the ends of said 25 loop member are welded, said shank being

within the nib and having an outer threaded end, a nut on said threaded end within the nib and non-rotatably engaging the same, and a non-rotatable ferrule bearing against the loop member and having a socket portion to receive the inner end of the nib. 30

3. The combination with a nib for snathes, of a nib iron having a snathe engaging loop formed of relatively thin pliable metal capable of ready bending under hand pressure to conform to the circumferential shape and size of the snathe, a nib, and a threaded connection operable by the turning of said nib, whereby said loop is made to conform to the snathe and secure the nib in place, substantially as set forth. 35

In witness whereof, I have hereunto set my hand and seal at Indianapolis, Indiana, this 25th day of September, A. D. nineteen hundred and fifteen.
